UNITED STATES PATENT OFFICE.

ARTHUR L. BRIDGHAM, OF BOSTON, MASSACHUSETTS, ASSIGNOR OF ONE-HALF TO
CHARLES H. SHERBURNE, OF BOSTON, MASSACHUSETTS.

LOCOMOTIVE.

1,354,238.

Specification of Letters Patent. Patented Sept. 28, 1920.

Application filed May 10, 1917. Serial No. 167,706.

To all whom it may concern:

Be it known that I, ARTHUR L. BRIDGHAM, of Boston, in the county of Suffolk and State of Massachusetts, a citizen of the United States, have invented a new and useful Improvement in Locomotives, of which the following is a full, clear, and exact description, reference being had to the accompanying drawings, forming a part of this specification, in explaining its nature.

The present invention relates to an improvement in steam locomotives and especially to locomotives of the superheater type.

The general object of my invention is to eliminate from the locomotive various objectionable parts heretofore employed and otherwise improve the locomotive as regards efficiency, safety and economy. In other words, my object is as follows:

20 To dispense with the relief valves customarily employed to prevent the formation of a partial vacuum within the cylinders during the drifting or idle running of the locomotive. These valves permit the objectionable entry of cold air into the hot cylinders and to the working parts and cause also condensation of steam and consequently the formation of water within the cylinders and the exhaust connections therefrom, which is 30 a thing to be avoided as is well known to these skilled in the art;

35 To otherwise prevent the collection of water within the cylinders, the cylinder saddles or steam chests and exhaust connections, and consequently to dispense with the use of cylinder cocks and saddle cocks as now usually employed;

40 To dispense with the usual blower pipe employed to produce a draft on the fire while the throttle valve is closed, and to utilize for such purpose the exhaust steam from the pump;

45 To provide through an improved exhaust pipe and nozzle means whereby the exhaust steam from the pump may be utilized to the best advantage for creating draft upon the fire when the locomotive is idle;

To dispense with drifting pipes usually employed to supply the cylinders with steam

directly from the boiler to act as a lubricator while the locomotive is drifting, and otherwise provide means whereby steam may be circulated in the cylinders at all times; to provide also means whereby all steam admitted to the cylinders while the locomotive is drifting or at rest may be utilized for the purpose of creating draft.

To dispense with the usual superheater damper customarily employed to prevent heat from the fire being drawn through the flues containing the superheater pipes when the throttle valve is closed, or, in other words, to provide means whereby heat may be drawn through these flues and also through the boiler tubes, which would otherwise be closed by the superheater damper, at all times, thereby preventing the plugging of the flues with soot, and otherwise improving the steaming capacity of the locomotive while at rest; in other words, to provide means whereby steam may be admitted to pass through the superheater pipes when the throttle valve is in a closed position and such steam afterward be utilized for purposes of creating draft.

To provide means whereby the pump, while the throttle valve is open, may be operated by superheated steam, with resulting advantages later to be mentioned:

The structural changes and additions by which the aforesaid objects are attained can best be seen and understood by reference to the drawings in which I have shown only those parts of a locomotive necessary to a proper understanding of the invention, and in which—

Figure 1 is a view partly in plan and partly in side elevation of the invention looked at as a working whole.

Figs. 2, 3 and 4 are sectional details of construction to which special reference will hereinafter be made.

Fig. 5 is a horizontal cross section of certain of the working parts later to be referred to and including especially the cylinder and exhaust connections.

Figs. 6 and 7 are vertical sections showing especially certain improved cylinder attach-

ments with certain of the parts occupying different operating positions.

Fig. 8 is a detail view of the throttle lever and connections.

5 Referring to the drawings:—

1 represents the shell of the boiler, 2 the steam dome, 3 the smoke chamber and 4 the smokestack. 5 and 6 are the cylinders and 7 and 8 the pistons within the cylinders. 9 10 is the saddle or steam chest on each cylinder. 10 are the sliding valves contained within the saddles and which control the entry of steam to the opposite ends of the cylinders by way of ports 11 and 12, respectively. 13 15 are the exhaust passages from the respective cylinders and which connect with an exhaust pipe 14. 15 are the boiler tubes. 17 are flues within which are contained superheater pipes. 18 is the throttle valve and 19 the 20 fixture for controlling the opening and closing of this valve. 20 is the casing inclosing the throttle valve. 21 is the dry pipe with which this casing connects and through which steam is conveyed beyond the throttle 25 valve. 23 are the superheater pipes through which the steam is conveyed from the dry pipe and which are contained, respectively, within the superheater flue 17 above referred to. 24 are steam pipes through which 30 the steam is directed from the superheater pipes into the saddles or steam chests 9 and thence to the respective cylinders. Other parts comprise the pump 26, shown dia- 35 grammatically in dotted lines, and 27 the fountain to which the steam is directed from the boiler through a leading-in pipe 28 for purposes of distribution.

The above structural parts are those common to locomotives of the type specified and 40 are referred to in order to obtain a proper understanding of my invention, to which attention will now be directed.

30 indicates the exhaust pipe from the pump having branches 32 and 33, respectively. 45 Of these branches the branch 32 connects with the rear end of the dry pipe 21 and accordingly discharges directly into the dry pipe. The branch pipe 32 has in it a one-way by-pass valve 34 (see Fig. 3) 50 which permits of the exhaust being admitted into the dry pipe when the throttle valve is closed, but which prevents steam backing up from the dry pipe through the pipe connection 32 when the throttle valve is 55 open. The branch pipe 33 connects with a fixture for discharging into the exhaust of the locomotive, as will later be explained. Attention is also directed at this point to a pipe connection 35 extending from the pipe 60 33 and connecting directly with the exhaust. This pipe has in it a one-way by-pass valve 36 which permits the passage of fluid pressure only in the direction of the arrow adjacent the valve.

65 Arranged beneath the cylinders 5 and 6

of the locomotive and fixed to them by pipe connections to which reference will presently be made, are valvular casings 38 and 39, respectively. Of these casings, the casing 38 is preferably arranged beneath the 70 left cylinder of the locomotive and the casing 39 beneath the right. The casing 38 (see Fig. 7) is of a generally tubular form, the rear end portion 40 thereof being of a slightly enlarged bore as compared with the 75 rest of the casing. The ends of the casing are closed by plugs 41 and 42, respectively, and about the middle of the casing, or in it about midway, relatively, between the two ends of the adjacent cylinder, the casing is 80 provided on the inside with an annular rib 43 forming a valve seat. Interposed between the casing and the adjacent cylinder are pipe connections 45. These pipe connections support the casing and provide communication 85 between the interior of the casing and the opposite ends of the adjacent cylinder. A further pipe connection 46 extends from the forward end of the casing, which projects beyond the forward end of the cylinder and 90 affords communication between the interior of the casing and one of the passages 13 of the exhaust.

Located within the casing are a series of valves 48, 49, 50 and 51 mounted upon a 95 common valve stem 52. These valves, with the exception of the valve 49, have a sliding fit within the bore of the casing and accordingly, as bearings, act to center the stem 52 upon which they are mounted. The 100 valves are slidable with a limited forward and reverse movement. In Fig. 7 the valves are shown in full lines as occupying a reversed position, which is the normal position of the valves, while the dotted indication of the valvular structure represents their forward moved position, both positions being effected and maintained as will later be explained.

The valve 48 is mounted in the enlarged 110 portion 40 of the casing and is purposely larger than the other valves. The valve 49 is arranged upon the valve stem to close against the seat 43 on the casing. It is also to be observed that the portion of the casing 115 adjacent the valve 43 is enlarged so that steam may freely pass through the interior of the casing when this valve is open. The valve 50 is arranged upon the stem to close communication with the pipe 46 when the 120 valvular structure is occupying its normal or reversed position as above referred to, and to afford communication between this passage and the interior of the casing or that portion thereof into which the pipes 45 125 are leading from the opposite ends of the cylinder when the valvular structure is occupying its forward moved position as indicated in dotted lines.

The valve 51 is arranged upon the for- 130

ward end of the valve stem 52 and accordingly has a sliding fit within the forward end of the casing. As already indicated, the stem 52 is a hollow stem and between the valves 50 and 51 an opening is formed in the side of the stem. This opening, when the valvular structure is occupying its forward moved position, is in communication with a pipe 53 extending from the side of the casing. When the valvular structure is occupying its reversed position the valve 51 will close the entrance to the pipe 53.

The forward and reversed movement of the valve and stem may be defined in any suitable manner. According to the present construction the reversed or normal movement of the valvular structure is defined by the engagement of the valve 49 with its seat 43, while the forward movement of the valve 20 is defined by the engagement of the valve 48 with the annular edge 54 of the casing or that edge by which the casing is enlarged to form the portion 40 thereof within which the valve 48 is contained.

As will later be more clearly explained, the valves are moved to, and maintained in, their normal or reversed position when steam is admitted to the cylinder upon the opening of the throttle valve, and this result is effected by reason of the fact that the steam will enter the interior of the casing through the pipe connections 45 (assuming the valves to be in a forward moved position) and operate upon the valves 48, 49 and 50. On account, however, of the valves 48 and 49 presenting a relatively larger face than the valve 50, the steam will accordingly operate to move the entire valvular structure to its reversed position and maintain it in such position as long as the throttle valve remains open and the steam pressure within the cylinder continues.

The valvular structure is moved from its normal or reversed position to a forward position, as will later be explained, when the throttle valve is closed, which relieves the pressure within the cylinder, and is effected by the admission of steam directly from the boiler through a pipe connection 55 tapped into the end of the plug 41 at the rear end of the casing 38. This occurs when the throttle valve is closed, as will later be explained. Steam so admitted will exert its pressure upon the valve 48 acting as a head or plunger, and thereupon the valvular structure will be moved to its defined forward position and maintained in such position as long as the pressure admitted through the pipe 55 is continued.

The casing 39 attached to the cylinder 6 on the right side of the locomotive is substantially like the cylinder 38, being of a generally tubular form and the rear end portion thereof having a slightly enlarged bore as compared with the rest of the casing.

The ends of the casing are closed by plugs 59 and 60, respectively, and at about the middle of the casing or in it about midway, relatively, between the two ends of the adjacent cylinder 6 the casing is provided on the inside with an annular rib 61 providing a valve seat. Interposed between the casing 39 and the adjacent cylinder 6 are pipe connections 63. These pipe connections support the casing and provide communication between the interior of the casing and opposite ends of the cylinder.

Connecting with the rear end of the casing; in other words, with the enlarged portion 58 thereof; is the exhaust pipe 33 from the pump, and connecting also with the same portion of the casing just forward of the pipe 33 is a pipe 64 which connects with the passage 13 of the exhaust.

A further pipe 65 extends from the forward end of the casing, which projects beyond the forward end of the adjacent cylinder and affords communication between the interior of the casing and the passage 13 of the exhaust.

Located within the casing 39 are a series of valves 66, 67, 68, 69 and 70, all mounted upon a common hollow valve stem 71. All these valves, with the exception of the valve 68, have a sliding fit within the bore of the casing and accordingly act as bearings to center the stem 71. The valves are slidable with a limited forward and reverse movement. In Fig. 6 the valves are shown in full lines as occupying a reversed position, while the dotted indication of the valves represents their forward moved position, both positions being effected and maintained as will later be explained.

Both the valves 66 and 67 are contained in the enlarged portion 58 of the casing and are purposely larger than the other valves. These valves are so relatively arranged upon the valve stem 71 that when the valvular structure is occupying its reversed position, both the pipe 33 and the pipe 64 will have communication with that interior portion of the casing lying between the two valves and communication will accordingly be obtained between the pipe 33 and the exhaust. The arrangement of the valves is such, however, that when the valvular structure is moved forward to its determinate forward position, the valve 66 will close communication between the pipe 33 and the pipe 64, and accordingly with the exhaust.

The location of the valve 67 is also such that steam admitted to the cylinder cannot enter either the pipes 33 or 64 by way of the casing 39, whether the valvular structure in it is occupying a forward or a reversed position.

The valve 68 is arranged upon the valve stem to close against the seat 61 within the casing. It is also to be observed that the

portion of the casing adjacent this valve 68 is so enlarged that steam may freely pass through the interior of the casing by this valve when open.

- 5 The valve 69 is arranged upon the stem to close communication with the pipe 65, when the valvular structure is occupying its reversed position; and to afford communication between this pipe and the interior of 10 the casing, or that portion thereof into which the pipes 63 are leading from the opposite ends of the cylinder, when the valvular structure is occupying its forward position as indicated in dotted lines.
- 15 The valve 70 located at the forward end of the valve stem acts as a sliding bearing and also operates to close communication between the forward end of the casing and the pipe 65, when the valvular structure is 20 occupying a reversed position.
- Leading into the forward end of the casing through the plug 60 is the pipe 53 which extends from the casing 38 as explained above.
- 25 The extent of forward and reverse movement of the valvular parts in the casing 39 are defined in any suitable manner. According to the present construction the reverse movement is defined by the engagement 30 of the valve 68 with its seat 61, while the forward movement of the valves is defined by the engagement of the valve 67 with the annular edge 73 of the casing or that edge by which the casing is enlarged 35 to form the portion 58 thereof. The valves are moved to, and maintained in, their normal or reversed position when steam is admitted to the cylinder 8 upon the opening of the throttle valve. When the throttle 40 valve is opened steam will enter the interior of the casing through the pipe connections 63 (assuming the valves to be in a forward moved position) and operate upon the valves 67, 68 and 69. On account of the 45 valves 67 and 68 presenting a relatively larger surface than the valve 69, the steam will act to move the entire valvular structure to its reversed position and maintain it in such position as long as the throttle 50 valve remains open and the steam pressure within the cylinder continues. On the other hand, the valvular structure within the casing 39 is moved from its reversed position to a forward position when the throttle 55 valve is closed, which relieves the pressure within the cylinder, by the admission of steam from the pipe 55, which passes through the stem 52 and out of the casing 38 by way of the pipe 53 into the forward 60 end of the casing 39 and thence through the hollow stem 71 to act upon the forward end of the valve 66, acting as a head or plunger, and thereupon the valvular structure will be moved to its defined forward position and 65 maintained in such position as long as the

pressure admitted through the pipe 55 continues.

Steam is admitted to the pipe 55 simultaneously with the closing of the throttle valve in the following manner, which is a 70 tentative arrangement and shown only for purposes of illustration:

Extending from the fountain 27 is a pipe connection 75 which connects with a valve casing 76 (see Fig. 2) having within it a 75 valve seat 77 against which closes a valve 78 having a stem 79. The pipe 55 connects with a chamber 80 of the casing forward of the valve and consequently the valve controls communication between the pipe 75 80 and the pipe 55, which enters the casing back of the valve. The stem 79 of the valve extends through the port controlled by the valve and thence through the wall of the casing and, bearing against this stem is a 85 lever 81 pivotally secured to the casing 76, and bearing against this lever is the throttle lever 82.

According to the arrangement of the parts, steam pressure entering the fountain 90 by way of the pipe 75 will enter the casing at the rear of the valve 78 and bearing against this valve will hold it normally closed upon its seat and prevent steam from the boiler entering the pipe 55. The closure 95 of the valve 78 is permitted by the pulling outward of the throttle lever 82 for opening the throttle valve, which permits the lever 81 to move outward and the valve 78 to close. When, however, the lever 82 is pushed inwardly for closing the throttle valve, it will at the same time push against the lever 81 and open the valve 78, which remains open allowing steam from the boiler to enter the pipe 55 as long as the throttle valve 82 remains closed.

Attention will now be directed to the exhaust pipe 14 which is specially constructed to form an operating part of the present construction.

The exhaust pipe 14 is provided at its upper end with an internal annular rib or edge 83 and beyond this a divergent nozzle 84. Resting normally upon the rib 83 forming a seat is a cone 85 of considerable weight 115 and which normally closes the end of the exhaust pipe excepting for ports or openings 86 through the cone. Centrally disposed within the exhaust pipe is a rib or post 87 which is fixed to, or forms an integral part 120 of, the bridge of the locomotive lying between the cylinders. This post bears upon its upper end a cylinder 90 the upper end of which is open to the chamber of the exhaust pipe. Within the cylinder 90 is a 125 piston 92 having a piston rod 93 which extends upwardly first through a web 94 on the inside of the exhaust pipe and then through the cone 85, and bears upon its end above the cone a spreader 96. The cone 130

85 is fixed to the piston rod 93 and consequently the cone and piston 92 are movable together. As the cone is moved onto and off its seat 84 it will be held centrally disposed by the piston rod, held centrally disposed by the bearing of the piston 92 within the cylinder 90 and also by the bearing of the rod within the web 94 acting as a guide for it.

10 The arrangement of the parts is such that, when the cone is resting upon its seat, the piston 92 will assume a position just adjacent the bottom of the cylinder within which it is contained. Any upward movement of 15 the cone and piston is defined as to extent by the engagement of the piston with the web, this engagement taking place before the piston leaves the cylinder.

Attention is also directed to the ports 97 20 in the side of the cylinder 90 which provide ingress for fluid pressure from the chamber of the exhaust pipe into the cylinder. These ports are arranged just above the bottom of the cylinder and are closed by the piston 25 when the cone 85 is resting upon its seat, but are opened as the cone is moved upwardly off its seat, raising the piston, when the fluid pressure from the chamber of the 30 exhaust pipe may enter the cylinder beneath the piston.

The pump 26 is operated by steam directly from the boiler when the throttle valve is closed, the steam being admitted to it by way of the fountain. When, however, the 35 throttle valve is open, the pump is operated by superheated steam admitted to it by way of one of the steam chests of the locomotive. For this provision is made as follows:—

As previously pointed out, steam from 40 the fountain will be admitted into the chamber 80 of the valve casing 76 forward of the valve 78 therein when the throttle valve is closed and automatically and simultaneously with such closure. Steam so admitted will 45 be directed therefrom through pipe connections 100 and 101 directly to the pump for operating it (see Fig. 1). In the pipe 100 is a one-way by-pass valve 102 in construction substantially like the valve 34 shown 50 in Fig. 4, which admits of the passage of steam in the direction of the arrow adjacent the pipe 100, but prevents the passage of steam in a reverse direction. Connecting also with the pipe 101 is a pipe 103 connecting with one of the steam chests 9 of the locomotive. This pipe has in it a one-way 55 by-pass valve 104 substantially like the valve 102 and admits only of the passage of steam in the direction of the arrow indicated adjacent this pipe. In other words, when the throttle valve is open and steam is cut off from the pipe 100, it may enter by way of the pipe 103 from the steam chest.

The general operation is as follows, reference being made to the periods when the

throttle valve is open during the ordinary running of the locomotive, when the throttle valve is closed during the idle running or drifting of the locomotive, and when the locomotive is at rest:—

The throwing of the lever for opening the throttle valve allows steam entering by way of the pipe 75 from the fountain 27, to close the valve 78. Thereupon steam pressure will be cut off from the pipes 55 and 100.

Simultaneously with this operation steam from the boiler will enter, by way of the dry pipe and subsequent connections, and be supplied to the respective cylinders for operating the pistons. As the steam enters 80

the cylinders it will pass out of the same by way of the pipes 45 and 63, respectively, and into the valve casings 38 and 39 arranged below the cylinders, and thereupon

will move into a reversed position the valves 85 contained in the respective casings as above described. Such operation will prevent steam entering the casings from passing out of the same through any of the pipes connecting with them, and the closing of

the valves 49 and 68, respectively against their valve seats prevents any circulation of steam between the two ends of each of the cylinders. Thereupon steam entering

the cylinders will operate the pistons in the 95 usual manner. In other words, all the pressure entering the cylinders will be utilized for operating the pistons. During the operation of the pistons steam will exhaust from the cylinders into the exhaust pipe

100 where the steam pressure will bear upwardly against the under side of the cone 85 and downwardly against the upper side of the piston 92. Inasmuch as the under side

105 of the cone presents a larger surface than the top side of the piston the pressure will act to lift the cone 85 off its seat at the upper end of the pipe. As the cone is lifted it lifts the piston with it. As the piston is raised above the ports 97, the pressure is

110 then admitted beneath the piston and will then act both against the under side of the cone and the under side of the piston whereupon the cone will be maintained in an elevated position as long as the pressure con-

115 tinues permitting the exhaust from the cylinders to freely pass out of the exhaust pipe into the stack. When the cone is lifted into an elevated position it of course permits of the free escape of the steam from the ex-

120 haust pipe, but, owing to the fact, as stated above, that the steam pressure within the exhaust pipe is bearing against both the under side of the cone and the under side of the piston, a very slight pressure within the

125 exhaust pipe will operate to maintain the cone in its elevated position, the parts being preferably so arranged that about two pounds pressure of steam within the exhaust pipe will effect this result, which is obtain-

70

130

able on account of the very large volume of steam entering the pipe. The steam will escape from the exhaust pipe around the cone into the stack in the form of an annular diverging column.

During this same period, steam being cut off from the pipe 100 on account of the closure of the valve 78, the pump will be operated by superheated steam entering by way of the pipe 103 from the steam chest 9. The steam will exhaust from the pump by way of the pipe 33 inasmuch as the one-way valve 34 will be held closed against the pressure of the exhaust by the greater pressure of steam within the dry pipe. The steam exhausting from the pump through the pipe 33 will pass into the casing 39 and escape therefrom through the pipe 64 directly into the exhaust.

Assuming now that the throttle valve is closed during the running of the locomotive and that the locomotive is idling or drifting: When the throttle lever 82 is moved for closing the throttle valve it will engage the lever 80 and open the valve 78. Thereupon pressure from the fountain will be admitted to the pipe 55 and this pressure will immediately operate to simultaneously throw the valves contained within the casings 38 and 39 into their respective forward moved positions and maintain them in such positions as previously described. The immediate consequence of this operation is that the exhaust from the pump can no longer enter the casing 39 to discharge through the pipe 64 into the exhaust of the locomotive for the reason that the valve 66 in the casing 39 will be moved by the outlet of the pipe 33 (see Fig. 6) and consequently will cut off communication between it and the pipe 64. The exhaust from the pump being thus cut off from the pipe 33, will accordingly be diverted to pass through the pipe 32 by the valve 34 into the dry pipe for the steam pressure within the dry pipe is cut off through the closing of the throttle valve, which permits of the exhaust from the pump entering the dry pipe by way of the pipe 32 and by the valve 34, as before noted. The exhaust steam so entering the dry pipe will pass through it and through the superheater pipes, thence through the steam pipes 24 into the respective steam chests and be supplied to the cylinders in the usual manner. Simultaneously with the entry of the exhaust steam from the pump into the dry pipe that steam admitted by way of the pipe 55 will also discharge into the dry pipe. As previously described, steam entering by way of the pipe 55 will pass through the valve stems contained in the respective valvular casings 38 and 39 and discharge into the rear end of the casing 39 to act upon the valve 66 for

moving forward the valvular structure contained within this casing. When the steam first enters the rear end of the casing 39 for moving forward the valvular structure contained within it, the valve 66 will be occupying a position cutting off communication between the rear end of the casing 39 into which the steam is discharging and the pipe 33 which is the exhaust pipe from the pump when the throttle valve is open. As the valvular structure in the casing 39 is moved forward by the steam pressure, the valve 66 will move forward by the entrance of the pipe 33 and close communication between this pipe and the pipe 64 connecting with the exhaust. The valve 66 will also prevent the steam admitted through the pipe 55 into the rear end of the casing 39 from passing out of the same by way of the pipe 64 connecting with the exhaust, but will permit the steam to pass out by way of the pipe 33, and the steam so admitted will pass upwardly through the pipe 33, thence through the pipe 32 to mingle with the exhaust coming from the pump and with it pass by the valve 34 into the dry pipe. Inasmuch as the steam is continuously being admitted through the pipe 55 when the throttle valve is closed, steam will accordingly be admitted into the dry pipe and subsequent connections when no steam is exhausting from the pump or when the pump is not running. The effect is that steam will always be discharging into the dry pipe and accordingly into the superheater tubes and subsequent connections, both during the running of the locomotive and when it is at rest and also when the pump is not running.

The relief of the cylinders during the idle running of the locomotive will be by way of the dry pipe, exhaust from the pump, and pipe 55. The entry of the exhaust steam from the pump and from the pipe 55 into the cylinders will have no active effect upon the pistons owing to the open positions of the valves 49 and 61 in the casings below the respective cylinders, for the open positions of these valves afford communication between the ends of each of the cylinders by way of the respective casings 38 and 39. Steam will exhaust from the cylinders 5 and 6 into the exhaust pipe in the usual manner, that is, through the ports 11 or 12 depending upon relative positions of the pistons and the slide valves 10. Steam will also exhaust from the cylinders through the pipes 46 and 65, respectively, by way of the respective valve casings, inasmuch as the moved position of the valves contained within the casings 38 and 39 permits of such outlet.

The exhaust steam from the pump 6 and the steam admitted from the boiler by way of the pipe 55 will be utilized for the crea-

tion of draft on account of the building up of pressure within the exhaust pipe and other connections, as will now be explained.

- When the throttle valve is closed the pressure before admitted to the exhaust pipe with the throttle valve open, immediately drops and the cone 85 will resume its seat closing the end of the exhaust pipe excepting for the ports 86 through the cone.
- 10 The settling back of the cone upon its seat moves the piston 92 downwardly within the cylinder 90 in which it is contained and by the ports 97, closing these ports. Now, as the pressure from the pump exhaust and pipe 55 enters the exhaust pipe it cannot readily escape and consequently pressure will immediately begin to build therein. Such pressure will bear upwardly against the under side of the cone 85 and downwardly against the upper side of the piston 92. These parts are of such proportion and weight that the cone will not be lifted for relieving the pressure until the pressure has reached a certain point, for example, ten 25 pounds to the square inch. When the pressure reaches such point it will operate to lift the cone off its seat whereupon the exhaust pipe will be relieved of the steam pressure within it and the cone will settle back on its seat, the operation being repeated when the pressure within the exhaust pipe again becomes sufficient to raise the cone.
- As stated above, the exhaust steam from the pump and from the pipe 55 builds up pressure within the exhaust pipe. The building up of pressure, however, is not restricted to the exhaust pipe, for pressure is also built up in all the connections into 30 which the steam is discharging, including the dry pipe and all subsequent connections between it and the exhaust pipe, including the superheater pipes, steam chests, cylinders, exhaust passages and auxiliary valvular casings. All of these parts collectively form a reservoir for the steam. The pressure thus built up within the exhaust pipe will be insufficient to exert any deleterious back pressure upon the pump owing to the 35 fact that the pump is being operated by steam at a very much higher pressure than that influencing the cone. Neither will the steam pressure thus contained have any effect upon the pistons for operating them inasmuch as the pressure will be the same on both sides of the respective pistons, the two cylinders, as stated above, forming a part of the reservoir within which the pressure is contained.
- 40 The operation of the piston during the drifting of the locomotive will cause more or less churning and circulation of the steam, and such circulation is further permitted by the one-way valve 56 which permits the pressure from the exhaust pipe

back through the pipe 35 into the pipe 33 which connects with the pump exhaust pipe 32 and thus with the dry pipe.

Substantially the same operation ensues while the locomotive is at rest as when it is drifting. Of course at such time the slide valves and pistons will be at rest. Steam, however, admitted into the cylinders can freely exit therefrom through one or the other of the outlet ports 11 or 12 at one 70 end or the other of the respective cylinders owing to the fact that the slide valves will at no time be in a position to close both of these ports. Accordingly entry is obtained to the exhaust from one end or the other of the respective cylinders. Moreover, even if the slide valves were in a position to close both of the ports 11 and 12, yet the steam admitted to the cylinders could always escape therefrom by way of the pipes 80 46 and 65, which are in communication with the chambers of the respective cylinders and connect with the exhaust as above noted when the throttle valve is closed.

As previously pointed out, the pump will 90 be operated when the throttle valve is closed by steam from the boiler entering by way of the fountain and pipe 100.

From the above described construction and mode of operation it will be seen that 95 the customary relief valves are entirely dispensed with and there is no inrush of cold air which would act to condense the steam, nor is there any undesirable escape of steam from around the front of the locomotive, 100 which is a most undesirable factor, owing to the fact that the steam (and in the present type of locomotive superheated steam) is being admitted to the cylinders at all times, and there is no opportunity for condensation of steam or the formation of water within the cylinders or adjacent connections. Moreover, even if some water should form it would gravitate into the respective casings 38 and 39 arranged below 110 the respective cylinders, and this water would become vaporized when steam was admitted (as it is admitted during the idle running of the locomotive and while it is at rest) into and through the stems 52 and 115 71, respectively, extending through these casings.

The usual blower pipe which customarily discharges into the smoke arch of the locomotive is dispensed with in the present instance. Instead, the exhaust steam from the pump and also the steam admitted by way of the pipe 55 and utilized for creating draft upon the fire when the throttle valve is closed. The steam admitted through the 120 pipe 55 is continued all the time the throttle valve remains closed and consequently steam will be admitted for the creation of draft when the pump is not running and there is no exhaust steam from it. More- 130

over, the pipe 55 will act as a blower pipe, that is, in case the engineer desires to create a forced draft upon the fire when the locomotive is at rest, and accordingly on this account the pipe 55 would naturally have a valve in it which is not shown in the present instance, but which would regulate the amount of steam admitted through this pipe. The advantage of the admission of steam in this way for the creation of draft is that the steam passes through the cylinders and connections keeping them warm and lubricated all the time the throttle valve is closed and especially during the drifting of the locomotive, thereby dispensing with the necessity for the usual drifting pipes, which are used for a similar purpose. A further advantage resides in the fact that the more steam there is admitted for increasing the draft, the more steam will be admitted to circulate through the superheater units, cylinders and other connections.

The ordinary superheater damper may be dispensed with for the reason that steam is being admitted at all times through the superheater pipes or units. The reason why the superheater damper is necessary in a locomotive as ordinarily constructed is that when the throttle valve is closed steam is no longer passing through the superheater pipes or units, and accordingly the heat from the fire can no longer be drawn through the flues containing the superheater pipes. Consequently these flues are cut off by the superheater damper. The closing of the superheater damper very materially decreases the efficiency of the locomotive, for when it is closed a large percentage of the boiler tubes are also cut off, as well as the flues which contain the superheater pipes, and it becomes practically impossible to build up steam as long as the superheater damper remains in a closed position.

The operation of the pump by means of superheated steam when the throttle valve is open, is an advantage inasmuch as the superheated steam is more efficient for operating the pump than ordinary saturated steam, for the superheated steam will not give up its pressure, or there is no fall in the pressure of the superheated steam, until the superheat in it is given up.

Having thus fully described my invention, I claim and desire to secure by Letters Patent of the United States:—

1. In a steam locomotive, the combination with the boiler, cylinders and pistons, steam connections through which steam from the boiler is directed to the cylinders for actuating the pistons, a throttle valve in said connections, and exhaust connections from the cylinders, including a draft creating device, of means whereby steam may be supplied to the cylinders when the throttle

valve is closed, means whereby the steam thus supplied will have access to opposite sides of the pistons within the respective cylinders and afterward pass to the exhaust connections and draft creating device, and means for preventing the free escape of steam, supplied and exhausting as aforesaid when the throttle valve is closed, from the draft creating device until pressure has been obtained by accumulation of steam therein. 75

2. In a steam locomotive, the combination with the boiler, cylinders and pistons, steam connections through which steam from the boiler is directed to the cylinders for actuating the pistons, a throttle valve in said connections, exhaust connections from the cylinders, a draft creating device provided with means whereby a free escape of steam from said device is prevented until pressure has been attained by accumulation of steam 85 therein, means for admitting steam to said device when the throttle valve is closed and means whereby the steam so admitted to said device may first be directed to pass through said cylinders and connections leading thereto. 90

3. In a steam locomotive, the combination with the boiler, cylinders and pistons, steam connections through which steam from the boiler is delivered to the cylinders for actuating the pistons, a throttle valve in said connections, and exhaust connections from the cylinders comprising in part an exhaust pipe, of means whereby steam is fed into said steam connections to pass into and through said cylinders and thence into the exhaust connections and exhaust pipe when the throttle valve is occupying a closed position, a valvular means for controlling the passage of steam through said pipe and throttling the exhaust steam admitted to said pipe to develop pressure therein while the throttle valve is closed, said valvular means being movable to relieve the pressure within said pipe when it reaches a determinate amount, and means for controlling the steam admitted during the closure of the throttle valve whereby it will have no influence to move said pistons. 100 110

4. In a steam locomotive, the combination with the boiler, cylinders and pistons, steam connections through which steam from the boiler is directed to the cylinders for actuating the pistons, a throttle valve in said connections, and exhaust connections from the cylinders, including a draft creating device, of means whereby steam may be supplied to the cylinders when the throttle valve is closed, means whereby the steam thus supplied will have access to opposite sides of the pistons within the respective cylinders and afterward pass to the exhaust connections and draft creating device, and means whereby the steam so supplied and exhausting as aforesaid when the throttle 120 125 130

valve is closed may be accumulated within said respective cylinders, and connections leading to and from the same and in said draft creating device and pressure therein 5 attained before being allowed to escape from said device.

5. In a steam locomotive, the combination with the boiler, cylinders and pistons, steam connections through which steam 10 from said boiler is directed to the cylinders for actuating the pistons, a throttle valve in said connections, exhaust connections from the cylinders including a draft creating device, a steam pump, steam connections for 15 operating the pump and exhaust therefrom, of means whereby the exhaust steam from the pump may be directed into and through the said steam connections leading to said cylinders, through the cylinders and exhaust 20 connections therefrom when the throttle valve is closed, means whereby the exhaust steam from the pump thus admitted to the cylinders may be admitted to opposite sides of the respective pistons, and means where- 25 by the free escape of steam, so supplied and exhausting as aforesaid when the throttle valve is closed, from said draft creating de- vice will be prevented until pressure has been obtained by accumulation of steam 30 therein.

6. In a steam locomotive, the combination with the boiler, cylinders and pistons, steam connections through which steam from the boiler is directed to the cylinders for actuating the pistons, a throttle valve in said 35 connections, and exhaust connections from the cylinders, of connections affording communication between the ends of each of the respective cylinders, valves for controlling 40 such communication arranged whereby they may move to and maintain a closed position shutting off communication between the ends of each of the respective cylinders when the throttle valve is open, means whereby steam 45 may be directed to open said valves and hold them open when the throttle valve is closed, and means whereby the steam thus introduced for opening the valves and holding them open will afterward be directed 50 into the steam connections leading to the respective cylinders and to said cylinders to circulate therethrough.

7. In a steam locomotive, the combination with the boiler, cylinders and pistons, steam 55 connections through which steam from the boiler is directed to the cylinders for actuating the pistons, a throttle valve in said connections, and exhaust connections from the cylinders, of connections affording communication 60 between the ends of each of the respective cylinders, valves for controlling such communication arranged whereby they may move to and maintain a closed position shutting off communication between the 65 ends of each of the respective cylinders

when the throttle valve is open, means whereby steam may be directed to open said valves and hold them open when the throttle valve is closed, and means whereby the steam thus introduced for opening the valves 70 and holding them open will afterward be directed into the steam connections leading to the respective cylinders and to said cylinders to circulate therethrough and exhaust therefrom, and means whereby the steam 75 thus exhausting may afterward be utilized for purposes of creating draft.

8. In a steam locomotive, the combination with the boiler, cylinders and pistons, steam connections from said boiler leading 80 to said cylinders for delivering steam there- to for actuating the pistons, a throttle valve in said connections between the boiler and the cylinders, exhaust connections from the cylinders, a steam pump, steam connections 85 for operating the pump and exhaust there- from, connections for affording communica- tion between the ends of each of the respec- tive cylinders, valves for controlling such communication arranged whereby they may 90 move to, and maintain, a closed position shutting off communication between the ends of each of the cylinders when the throttle valve is open, means whereby steam may be directed to open said valve when the throttle 95 valve is closed, and means whereby both the exhaust steam from the pump and the steam introduced for operating said valves may be directed into the steam connections lead- ing to the cylinders when the throttle valve 100 is closed.

9. In a steam locomotive, the combination comprising the respective cylinders, valve casings arranged adjacent and below the same and affording communication between 105 the ends of each of the cylinders, valves ar- ranged within said casings, hollow valve stems carrying said valves, a pipe connec- tion between the hollow stem of one of said casings and the other casing, means whereby 110 said valves may be moved to occupy a cer- tain determinate position upon the entry of steam to said cylinders when the throttle valve is opened, and means for introducing steam into one of said casings when the 115 throttle valve is closed to act upon the valvular structure therein and pass through the hollow stem thereof, thence enter the other of said casings and pass through the hollow stem thereof and act upon the valvu- lar structure therein substantially as de- 120 scribed.

10. In a steam locomotive, the combination with the boiler, cylinders and pistons, steam connections from said boiler leading 125 to said cylinders for delivering steam there- to for actuating the pistons, a throttle valve in said connections between the boiler and the cylinders, exhaust connections from the cylinders, a steam pump, steam connections 130

for operating the pump and exhaust therefrom, connections for affording communication between the ends of each of the respective cylinders, valves for controlling such communication arranged whereby they may move to, and maintain, a closed position shutting off communication between the ends of each of the cylinders when the throttle valve is open, means whereby steam may be directed to open said valves when the throttle valve is closed, means whereby both the

exhaust steam from the pump and the steam introduced for operating said valves may be directed into the steam connections leading to the cylinders to circulate therethrough and through said cylinders and exhaust therefrom when the throttle valve is closed, and means whereby the steam thus exhausting may afterward be utilized for purposes of creating draft. 15

ARTHUR L. BRIDGHAM.
